UNITED STATES PATENT OFFICE.

HEINRICH SCHNURRENBERGER, OF ZUG, SWITZERLAND, ASSIGNOR TO LANDIS & GYR, A.-G., OF ZUG, SWITZERLAND, A LIMITED-JOINT STOCK COMPANY OF SWITZERLAND.

CONTACT DEVICE FOR ELECTRIC-CLOCK SYSTEMS.

Application filed October 27, 1925, Serial No. 65,065, and in Switzerland October 28, 1924.

The invention relates to electrical circuit controlling devices, and more especially to such devices applicable to clocks and time measuring devices to capacitate them as master clocks or controlling devices or controlling instrumentalities for secondary clocks and other controlled devices.

Objects and advantages of the invention will be set forth in part hereinafter and in part will be obvious herefrom, or may be learned by practice with the invention, the same being realized and attained by means of the instrumentalities and combinations pointed out in the appended claims.

15 The invention consists in the novel parts, constructions, arrangements, combinations and improvements herein shown and described.

20 The accompanying drawings, referred to herein and constituting a part hereof, illustrate one embodiment of the invention, and together with the description, serve to explain the principles of the invention.

25 Of the drawings:—

Fig. 1 is a side elevation of a mechanism embodying the invention;

Fig. 2 is an elevation looking at Fig. 1 from the left;

Fig. 3 is a top plan of said mechanism;

30 Fig. 4 is a diagrammatic showing in greater detail of the circuit making and breaking, and polarity changing devices of Fig. 3.

The invention is directed primarily to providing a mechanism capacitated to be attached to clock mechanisms of usual or standard forms, to cooperate therewith, and whereby such clock mechanisms are transformed into master clocks, for one or more secondary clocks. The invention further provides mechanisms of the general kind described capacitated for similar master control of signal systems and the like.

35 The invention, broadly considered, is susceptible of embodiment in a plurality of forms for effectuating the functions described, the particular form depending, to a certain degree at least, upon the particular clock mechanism to which my invention is to be applied, as will be obvious to those skilled in the art.

In the present preferred embodiment of the invention a control mechanism for the controlled electrical circuit is connected to, and thereby caused to move synchronously with, a clock mechanism, preferably being connected

to a shaft in the clock mechanism. The controlled electrical circuit is thus governed to control the secondary clocks or like mechanisms or devices.

More particularly, in the present preferred embodiment, a toothed driving gear engages a pinion on a shaft which carries, besides the contacts, a brake wing or detent, which periodically or sequentially prevents the turning of the shaft by resting on a stationary pin. This shaft is carried by a swinging bail, which in turn is pivotally carried by the axle of the driving gear. Through the lifting of this bail by the driving gear, which is moving at a constant speed, the release of the brake-wing or detent from the stationary pin is effected, permitting the shaft to turn and the contacts to make the circuit. The making of circuits is only momentary, as, due to the falling back of the bail or swing, the shaft is returned to its original position, and is again prevented from turning by the brakewing again resting on the stationary pin. The contacts are connected to four circuit wires, two of which are the power line high and low potential wires and two of which are in the circuit of the controlled or secondary clock or other mechanism.

The foregoing general description, and the following detailed description as well, are exemplary and explanatory of the invention, but are not restrictive thereof.

Referring now in detail to the embodiment of the invention, illustrated herewith by way of example, a bracket 1 carries a shaft 2 which forms the axle of a toothed wheel 3. The hub of this toothed wheel 3 is provided with a slot 4, which permits the coupling of same with a shaft of an existing movement, which can be, for example, the hour axle of a clock.

Shaft 2 carries furthermore a bail 5, which carries a shaft 6. Upon this shaft 6, within the bail 5, there are placed, in this case, four pairs of contacts 7. These contacts 7 are eccentrically arranged on the shaft 6 and each single contact of each pair is placed on the shaft in opposite position to the other. The contacts 7 are all electrically insulated from each other, and from the shaft 6, in any known or other suitable manner. Outside of the bail 5, the shaft 6 reaches through an oval hole 8 of the bracket 1, and carries at its end a pinion 9, which pinion engages with the toothed wheel 3. The other end of shaft 6, also outside of the bail 5, carries a two-

armed brakewing 10, either arm of which may rest against a stationary pin 11. The block pin 11 is mounted in a block 12. The block 12 consists of insulating material and is fastened to bracket 1 by a screw 13. The block 12 carries also four contacts 14, each of which corresponds respectively with one pair of the contacts 7.

Two of these contacts 14 are connected to a battery B, and two others serve to make circuit, for example, in a system of electric secondary clocks S.

The described device can, for example, as already stated, be connected to a clock movement, for which purpose the plate 16 with hole 15 is provided. The connection is made by fitting one end of the hour axle of the clock into the slotted hub of the toothed gear 3, providing at the same time a pin on the hour axle which effects the coupling of the toothed gear 3 with the hour axle of the clock by catching into the groove 4.

The running of the clock effects the constant turning of the toothed gear 3, through which it also tends to turn the shaft 6. This is prevented, however, through the brakewing 10, which has one of its arms resting on the stationary pin 11, and shaft 6 is consequently lifted with bail 5. This causes the sliding of the arm of brakewing 10 on pin 11 until it is released from the pin, at which moment the bail 5 will fall back to its previous position through medium of the toothed gear 9 which is engaged with the toothed gear 3, and which actuates at that same moment the turning of the shaft 6. After half a turn this slipping back of bail 5, and consequent rotation of shaft 6, is arrested by the second arm of brakewing 10 which now has come to rest on pin 11. Through this operation circuit is made through the contacts 7 and 14 which touched each other for a moment, so that from the battery a momentary flow of current was sent to the secondary clocks. It will be clear that by reason of the two-armed member 10, shaft 6 makes a half revolution for each release of arm 10. There are two sets of contacts on shaft 6, four of which 7^a, 7^c, 7^e, 7^g, cooperate with contacts 14^a, 14^b, 14^c and 14^d on one half revolution of the shaft, and the other four of which, 7^b, 7^d, 7^f, 7^h, cooperate with the contacts 14^a, 14^b, 14^c and 14^d on the next succeeding half revolution of shaft 6 when it is again released by the clock mechanism.

As described before, two of the contacts 14 are connected to a battery, or other power source B, and the two others to a secondary mechanism S to be controlled. In the present example, contacts 14^b and 14^c may be considered as connected to the secondary mechanism, contact 14^a to the + side of the battery, and contact 14^d to the - side of the battery. The contact points 7 are then interconnected as follows:—7^a to 7^c and 7^e to 7^g;

and 7^b to 7^h and 7^d to 7^f. At the first half revolution of shaft 6, contact is made between 14^a, 14^b, 14^c and 14^d, and 7^a, 7^c, 7^e and 7^g, respectively, and the flow of current is effected through 14^a to 7^a to 7^c to 14^b and to the secondary mechanism, and then through 14^c to 7^e and 7^g, and thence to 14^d and back to the - side of the battery. At the second half revolution of shaft 6, contact is made between 14^a, 14^b, 14^c and 14^d and 7^b, 7^d, 7^f and 7^h, respectively, and the flow of current is effected from the battery through 14^a, 7^b to 7^f to 14^c, through the secondary mechanism, and then to 14^b to 7^d to 7^h to 14^d and to the - side of the battery. The contacts 7 are connected in a way that a change of polarity is effected at every making of circuit in the system of the secondary clocks, namely, considering first contacts 7^a, 7^c, 7^e and 7^g, the current flow through the secondary clocks, or corresponding devices would be from 14^b to 14^c and thence to the negative side of the battery. When, however, the mechanism is in the other position, and contact is made through 7^b, 7^d, 7^f and 7^h, then the current flow is from 14^a to 14^c, through the secondary clocks, or other devices, to 14^b, to 14^d and thence to the negative side of the battery. Thus there is effected a periodic or sequential change of polarity in the secondary clocks or other devices.

The ratio of the wheels 3 and 9 is such that a release of the brakewing 10 is effected every minute.

Due to the fact that the driving wheel 3 carries the weight of the bail 5 and the parts attached thereto during the entire time between the making of circuit, there is obtained a practical constant load on the clockwork by this contact device, so that the running of the clock is not disadvantageously affected by this installation.

The construction of this contact device as a unit makes it possible to install the same without difficulty in an existing clock, and to transform the clock therewith into a master clock for a system of secondary clocks.

Besides being used for the operation of secondary clocks this invention could also be employed for other purposes; it could be used, for example, in connection with signal devices and other installations. In such a case it would be necessary, however, to change the ratio of the wheels 3 and 9.

The invention in its broader aspects is not limited to the specific mechanisms shown and described but departures may be made therefrom within the scope of the accompanying claims without departing from the principles of the invention and without sacrificing its chief advantages.

What I claim is:—

1. An electric circuit controlling device including in combination a driving wheel having a shaft, a control shaft provided with

- contacts and mounted in a swingable support, pivotally supported on said wheel shaft, said control shaft being connectable to a shaft in a clock mechanism, and a detent therefor controllable by the clock mechanism. 5
2. An electric current controlling device including in combination a member actuated and periodically released by a time-measuring mechanism, a circuit having contact terminals and controlling a secondary mechanism, and means operated by the release of said actuated and periodically released member for momentarily closing the circuit at said terminals. 10
- 15 3. An electric circuit controlling device including in combination a member periodically released by a time-measuring mechanism, a circuit having contact terminals and controlling a secondary mechanism, and means operated by said periodically released member for momentarily closing the circuit at said terminals.
4. An electric circuit controlling device including in combination a member controlled in time by a time-measuring mechanism, a circuit controlling a secondary mechanism, and means operated by said time-controlled member for controlling and reversing the polarity of said circuit. 25
- 30 5. An electric circuit controlling device including in combination a member periodically released by a time-measuring mechanism, a circuit having contact terminals and controlling a secondary mechanism, and means operated by said periodically released member for momentarily closing the circuit at said terminals and changing its polarity. 35
6. An electric circuit controlling device including in combination a driving wheel hav-
- ing a shaft, a control shaft and circuit contacts governed thereby, means for operating the control shaft and a release device therefor operated from said driving wheel. 40
7. An electric circuit controlling device including in combination a plurality of line circuit terminals, a plurality of sets of terminal closing devices, and time controlled means for causing said sets of closing devices to successively close the plurality of terminals. 45
- 50 8. An electric circuit controlling device including in combination a plurality of line circuit terminals, a plurality of sets of terminal closing devices, polarity changing connections therefor, and time controlled means for causing said sets of closing devices to successively close the plurality of terminals to reverse the current in the circuit. 55
9. An electric circuit controlling device including in combination more than two terminals in a line circuit, more than one circuit closing device cooperating successively with each of said terminals, and time-measuring means for controlling the successive operation of said circuit closing devices. 60
- 65 10. An electric circuit controlling device including in combination more than two terminals in a line circuit, more than one circuit closing device cooperating successively with each of said terminals, polarity changing connections therefor, and time-measuring means for controlling the successive operation of said circuit closing devices to reverse the current in the circuit. 70

In testimony whereof, I have signed my name to this specification. 75

HEINRICH SCHNURRENBERGER.
